UNITED STATES PATENT OFFICE.

IRA G. HAZZARD, OF EAST PORTLAND, OREGON.

DESIGN FOR A FIRE-KINDLER.

SPECIFICATION forming part of Design No. 22,825, dated October 3, 1893.

Application filed May 6, 1893. Serial No. 473,315. Term of patent 14 years.

To all whom it may concern:

Be it known that I, IRA G. HAZZARD, of East Portland, in the county of Multnomah and State of Oregon, have invented a new and useful Design for Fire-Kindlers; and I do hereby declare the following to be a full, clear, and exact description of the invention, such as will enable others skilled in the art to which it appertains to make and use the same.

This invention is a design for a fire-kindler, and its leading features are the peculiar shape of the kindler block, and the peculiar shape and ornamentation of the handle.

The drawing hereunto annexed, fully illustrates my new design, and referring to said drawing, A, indicates the representation of a solid block, and B, indicates the representation of a handle attached to said block.

The block A, is essentially cubical in shape, and has all of its edges and corners beveled, ²⁰ as shown at a.

The handle B, is formed with straight members b, the bends b' and twisted portion b², terminating in a circular loop b³.

Having thus described my invention, what ²⁵ I claim is—

The design for a fire kindler, substantially as herein shown and described.

In testimony whereof I have signed this specification in the presence of two subscriv- ³⁰ ing witnesses.

IRA G. HAZZARD.
